UNITED STATES PATENT OFFICE.

JOHN HENRY BARKER, OF SHEFFIELD, ENGLAND.

FILE.

1,106,536.

Specification of Letters Patent.

Patented Aug. 11, 1914.

Application filed May 12, 1914. Serial No. 838,181.

To all whom it may concern:

Be it known that I, JOHN HENRY BARKER, M. I. Mech. E., a subject of the King of England, and a resident of Sheffield, in 5 Yorkshire, England, have invented certain new and useful Improvements in or Relating to Files, of which the following is a specification.

This invention relates to files of the kind 10 which are provided with clearance grooves of greater depth and pitch than the file-cuts for the escape of the filings, its object being to provide an improved arrangement of the clearance grooves in order to produce a more 15 efficient tool. According to the present invention, three different series of clearance grooves are provided, and of these, one series is arranged approximately at right angles to the axis of the file while the other two 20 series are inclined thereto and to each other. Preferably the inclination of the last two series is equal and the three series are so disposed as to divide the file surface into a number of equal triangular areas.

25 In the accompanying drawings:—Figure 1 is a plan of part of a single-cut file according to this invention. Fig. 2 is an elevation of Fig. 1.

Like letters indicate like parts throughout 30 the drawings.

In carrying out this invention three series of clearance grooves A, B and C are formed in the face of the file. Of these, the series A is arranged approximately at right angles 35 to the file axis, as shown in Fig. 1, while the two series B and C are both inclined thereto and to each other. The preferred disposition of the three series of clearance grooves is shown in Fig. 1, the inclination 40 of B and C to the axis being equal and all three joining the edge of the file at approximately the same place, thus dividing the file surface into a number of equal triangular areas. As illustrated, the series C is parallel 45 to the file cuts D although the inclined clearance grooves may be formed at a different angle with the file axis from the file cuts if desired. The clearance grooves may intersect one another or not as desired; in the 50 drawings only the series B and C intersect one another.

The present invention is primarily de-

signed for a single-cut file, but may be applied to a double-cut file.

The clearance grooves A, B and C may be 55 provided by any desired method. For example they may be made in an ordinary file cutting machine by increasing the power or the number of blows of the chisel, or they may be cut by a milling tool either before or 60 after the file-cuts D are made. In another method the deeper cuts or grooves are formed during the rolling of the file blank.

What I claim and desire to secure by Letters Patent is:—

1. In a file provided with clearance 65 grooves, the provision of three series of such grooves of which one series is arranged approximately at right angles to the file axis, while the other two series are inclined thereto and to each other substantially as set forth.

2. In a file provided with clearance 70 grooves, the provision of three series of such grooves of which one series is arranged approximately at right angles to the file axis, another series is parallel with the file-cuts 75 and the third series is at right angles to the file-cuts, substantially as set forth.

3. In a file provided with clearance 80 grooves the provision of three series of such grooves of which one series is arranged approximately at right angles to the file axis, while the other two series are so disposed in relation thereto and to each other as to 85 divide the file surface into a number of triangular areas of approximately equal size, substantially as set forth.

4. In a file provided with clearance 90 grooves, the provision of three series of such grooves of which one series is transverse, being arranged approximately at right angles to the file axis, while the other two series form diagonals between the members 95 of the transverse series, substantially as set forth.

In testimony whereof I have signed my name to this specification in the presence of two subscribing witnesses.

JOHN HENRY BARKER.
